VENTILATING MECHANISM.

1,115,479.

Specification of Letters Patent.

Patented Nov. 3, 1914.

Application filed June 8, 1912. Serial No. 702,390.

To all whom it may concern:

Be it known that we, AUGUSTINE R. AYERS and BERNARD A. STOWE, both citizens of the United States, and residents of Chicago, 5 county of Cook, and State of Illinois, and of Cleveland, county of Cuyahoga, and State of Ohio, respectively, have jointly invented a new and useful Improvement in Ventilating Mechanism, of which the following is a 10 specification, the principle of the invention being herein explained and the best mode in which we have contemplated applying that principle, so as to distinguish it from other inventions.

15 The present invention relates primarily to air current producing means of the kind known as rotary fans, which continually change the direction of the air currents produced thereby.

20 The object of the invention is the provision of a fan of this type, which will automatically revolve about a fixed axis by the positive operation of the fan motors, the design being such as to secure such positive 25 operation with a minimum expenditure of energy, and in such a form that the fan mounting may be capable of assuming a more or less ornamental form, as is desirable in rooms and railway coaches, and other 30 places where such rotary fans are generally employed.

A further object of the invention is the inclusion in a single compact fixture of the fan mechanism and a lighting device, so 35 that, particularly in the case of railway coaches and the like, where the ceiling is paneled and laid out with regard only to pendant lighting fixtures, and the amount of head-room is limited, the introduction of fans 40 may be made without destroying the proper symmetry and effect of the arrangement and with a minimum drop from the supporting ceiling. It is also objectionable in such locations to add to the number of fixtures depending from the ceiling, as would be necessary if separate ones were required for the support of the fan and lighting units.

To the accomplishment of the foregoing and related ends, said invention, then, consists of the means hereinafter fully described and particularly pointed out in the claims.

The annexed drawing and the following description set forth in detail certain mechanism embodying the invention, such dis- 55 closed means constituting, however, but one

of the various mechanical forms in which the principle of the invention may be used.

In said annexed drawings:—Figure 1 is a part side elevation and part vertical section of a combined lighting and fan fixture in 60 which have been embodied the several improvements above referred to; Fig. 2 is a horizontal section of such fixture taken on the line 2—2, Fig. 1; and Fig. 3 is a broken sectional view taken at right angles to the 65 plane of the section in Fig. 1.

The fixture illustrated in the foregoing drawing, as indicated, is designed to combine our improved fan, together with a light unit, in a unitary structure, said fixture being adapted to be secured directly to the ceiling. The base of the fixture accordingly consists of a plate or canopy 1 provided with holes 2 for securing or bolting it to such ceiling, to which plate is, in turn, attached 70 by means of screws 3 an interiorly threaded casting 4. In the latter is threaded a central stem 5 of hollow cylindrical form having a laterally extending up-turned flange 6 near its lower end, in which is carried a ball 70 race and balls 7. These form a bearing for a rotatable shell or hollow frame 8 from which the fans 9 are designed to be supported, as will be presently explained. This shell also has an interior bearing contact at 75 its upper end 10 with the casting 4 into which the stem is threaded, but the weight of the frame is sustained, as will be obvious, upon the ball bearing, thus leaving it free to rotate with a very slight expenditure of 80 power.

The fans 9 are not directly secured to the frame 8, but to a shell 11 of conical or skirted form that is securely attached at its upper smaller end to the lower end of said 95 frame, and that entirely incloses the lower flanged end of the central stem 5 and the ball bearing 7 carried thereby. The housings for the fan motors, which housings may be of any appropriate design, are supported on pedestals or studs 12 located near the lower edge of this skirted shell, the number of fans being ordinarily two, as shown in the drawing, although any number for which there is space may be so mounted. The fans 100 proper are carried by the forward ends of the motor shafts 14, while the rear ends of such shafts, which incline upwardly with respect to the central axis of the fixture, carry, or are connected with, speed reducing 105 110

- mechanisms 15 to which are secured beveled pinions 16, either of the frictional kind shown, or toothed, as may be preferred, depending upon the character of the service 5 and other conditions surrounding the use of the device. An approved construction of reducing mechanism is that shown in U. S. Letters Patent No. 988,043, but it will be understood that any suitable speed-reducing 10 mechanism may be introduced, as also that if the motor shaft be run slow enough it can carry the pinion directly, except that in such case the fan would have to be geared up instead of being mounted on the motor shaft. 15 Beveled pinions 16 engage an annular member or ring 17 supported from the casting 4 and having its contacting face 18 either smooth or toothed, depending upon whether a frictional or geared engagement 20 between the pinions and such member is desired. Where the former driving connection is utilized, the member is preferably slidably supported from the casting by means of pins 19 that enter vertical slots 20 in the latter, the weight of the member being depended upon to preserve the necessary frictional engagement with the pinions, while by leaving the member floating, as it were, it is free to accommodate itself to any 25 differences in the relative positions of the pinions, making the device in this respect automatically adjustable. 30 The upper portion of the structure between the canopy 1 and the skirted shell 11 is enclosed by another shell 21 that corresponds in form and ornamental design with such first named shell and hides the pinions, the annular member 17 and the casting 4, from which the structure as a whole depends. 35 Such upper shell is preferably divided on a diametrical line which includes the axes of the two pinions, openings being left through which the latter may project into engagement with the annular member. 40 Electrical connection from the leads to the respective motors is made through the medium of two contact rings 22 and 23 carried by an annular insulating base 24 that slips over the casting 4 and is supported thereby. 45 Coöperating with these rings respectively are two pairs of contact brushes 25 and 26 that are conveniently attached to the upper shell, one pair adjacent to each fan motor. Suitably insulated wires 27 lead from the 50 brushes to the motors, being carried beneath the lower shell 11, so as to be substantially entirely out of sight, as are also the connections 28 from the rings to the lead wires. 55 As stated, the fixture in hand is designed 60 to include a lighting unit along with the foregoing fan mechanism, and with this in view, a housing 29 for such unit and its glassware is provided, being attached directly to the lower end of the central stem 65 5 of the structure previously described.

Only the outer lower edge of this housing will extend beyond the skirted shell 11 that supports the fans and the two will normally be made to harmonize in design. To the lower edge of this casting, or rather to an ornamental ring in effect forming a part thereof, is hinged the annular support 30 for a glass bowl 31 or other desired inclosure for the under side of the lighting unit, a latch normally holding this support closed, 75 as will be readily understood. The lamp receptacle 32 is attached to the upper portion of the housing and may serve to carry both the lamp 33 and the shade or reflector 34, or the latter may, if desired, be otherwise supported as most convenient within the housing 29. The wiring 35 for the lamp is carried directly through the receptacle in the central opening in the stem of the fixture and is entirely independent of the wiring 80 connections 22 for the fan. Separate remote switches (not shown) will, of course, be provided for controlling the fan motors and lamp.

The mode of operation of the device 90 should be readily understood without other than brief description. The motors, upon closing the electric circuit which includes them, rotate their shafts and thus the pinions 16 through the medium of the reducing 95 mechanism 15; such pinions, by reason of their frictional or meshing contact with the annular member 17, effect the rotation of the entire rotatable supporting structure, including the frame 8, the shells 11 and 21 100 supported thereby, and the fans 9. Such rotation, of course, is about the vertical axis of the fixture. The lamp 33 may be turned on or off whenever desired by means of the switch which controls the separate circuit 105 including said lamp.

It will, of course, be understood that one motor only may be provided with positive driving connection with the annulus 18, or equivalent non-rotative element of the fixture, although a better balance is secured by the construction shown. It need also scarcely be remarked that the fans may be connected either in series or parallel as desired, only a single pair of contact members 110 22 and 23 being requisite in the latter case.

By the use of positive gears operated by one or more fan motors through suitable reducing mechanism in the fashion hereinbefore set forth, the fixture is caused to revolve 115 at any and all speeds of the motors. Thus at a reduced voltage, or when subjected to abnormal retarding forces, the fixture is still operative. Indeed, the arrangement lends itself to a speed adjustment by means of an 120 interposed resistance in the circuit leading to the fixture, an adjustment which cannot be successfully utilized in fixtures of this class depending for their operation upon the reactive forces on the blades. 130

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:—

- 10 1. In mechanism of the class described, the combination of a pendent support; a frame rotatably attached thereto; electric fans carried by said frame; an annular member on said support disposed adjacent to the 15 inner ends of said fans, said member being non-rotatably but freely vertically movable with reference to said support; and pinions on said motors having a driving engagement with the under face of said annular member, 20 whereby said frame is rotated upon operation of said fans.
2. In mechanism of the class described, the combination of a pendent support; a frame rotatably attached thereto; electric 25 fans carried by said frame, the shafts of the fan motors being inclined upwardly at their inner ends; an annular member on said support disposed adjacent to the inner ends of such shafts, said member being non-rotatably but freely vertically movable with reference to said support; and bevel pinions on 30 said motors having frictional driving engagement with the under face of said annular member, whereby said frame is rotated 35 upon operation of said fans.
3. In mechanism of the class described, the combination of a pendent support comprising a plate adapted to be attached to a ceiling or the like; a central stem threaded 40 into said plate and depending therefrom, said stem having a laterally extending flange near its lower end, and a ball-bearing on said flange; a hollow frame mounted on said bearing so as to be rotatable about said stem, said frame also having a lateral bearing at its upper end; a skirted shell depending from said frame; electric fans supported on said shell, the shafts of the fan motors being inclined upwardly at their inner ends; 45 an annular member attached to said plate so as to lie adjacent the inner ends of said fans, said member being non-rotatable but freely vertically reciprocable with reference to said plate, pinions on said fans having 50 a driving engagement with said annular member, whereby said frame is rotated upon operation of said fans; said annular member being weighted to adapt it to automatically adjust itself vertically into constant 55 driving engagement with said pinions.
4. In mechanism of the class described, the combination of a pendent support comprising a plate adapted to be attached to a ceiling or the like; a central stem threaded 60 into said plate and depending therefrom,
- 70 said stem having a laterally extending flange near its lower end, and a ball-bearing on said flange; a hollow frame mounted on said bearing so as to be rotatable about said stem, said frame also having a lateral bearing at its upper end; electric fans carried by said frame; an annular member attached to said frame so as to lie adjacent to the inner ends of said fans, said member being non-rotatable but freely vertically reciprocable with reference to said plate; and pinions on said fans having a driving engagement with said annular member, whereby said frame is rotated upon operation of said fans.
- 75 5. In mechanism of the class described, the combination of a pendent support comprising a plate adapted to be attached to a ceiling or the like; a central stem threaded into said plate and depending therefrom, 80 said stem having a laterally extending flange near its lower end, and a ball-bearing on said flange; a hollow frame mounted on said bearing so as to be rotatable about said stem, said frame also having a lateral bearing at its upper end; a skirted shell depending from said frame; electric fans supported on said shell, the shafts of the fan motors being inclined upwardly at their inner ends; an annular member attached to 85 said plate so as to lie adjacent to the inner ends of said fans, said member being non-rotatable but freely vertically reciprocable with reference to said plate; and pinions on said fans having a driving engagement with 90 said annular member, whereby said frame is rotated upon operation of said fans.
- 95 6. In mechanism of the class described, the combination of a pendent support comprising a plate adapted to be attached to a ceiling or the like; a central stem threaded into said plate and depending therefrom, 100 said stem having a laterally extending flange near its lower end, and a ball-bearing on said flange; a hollow frame mounted on said bearing so as to be rotatable about said stem, said frame also having a lateral bearing at its upper end; a skirted shell depending from said frame; electric fans supported on said shell, the shafts of the fan motors being inclined upwardly at their inner ends; an annular member attached to 105 said plate so as to lie adjacent to the inner ends of said fans, said member being non-rotatable but freely vertically reciprocable with reference to said plate; and pinions on said fans having a driving engagement with 110 said annular member, whereby said frame is rotated upon operation of said fans.
- 115 7. In mechanism of the class described, the combination of a pendent support comprising a plate adapted to be attached to a ceiling or the like; a central stem threaded into said plate and depending therefrom, 120 said stem having a laterally extending flange near its lower end, and a ball-bearing on said flange; a hollow frame mounted on said bearing so as to be rotatable about said stem, said frame also having a lateral bearing at its upper end; a skirted shell depending from said frame; electric fans supported on said shell, the shafts of the fan motors being inclined upwardly at their inner ends; an annular member attached to 125 said plate so as to lie adjacent to the inner ends of said fans, said member being non-rotatable but freely reciprocable with reference to said plate; a second shell, made up of separable sections, inclosing said frame and member and having apertures opposite said fans; and pinions on said fans extending through the apertures in said second shell and having a driving engagement with said annular member, whereby said frame is rotated upon operation of said fans.
- 130 8. In mechanism of the class described, the combination of a pendent support com-

prising a plate adapted to be attached to a ceiling or the like; a central stem threaded into said plate and depending therefrom, said stem having a laterally extending flange near its lower end, and a ball-bearing on said flange; a hollow frame mounted on said bearing so as to be rotatable about said stem, said frame also having a lateral bearing at its upper end; a skirted shell depending from said frame; electric fans supported on said shell, the shafts of said motors being inclined upwardly at their inner ends; a lamp fixture attached to the lower end of said stem so as to be partially inclosed by said shell; an annular member attached to said plate so as to lie adjacent to the inner ends of said fans, said member being non-rotatable but freely vertically

reciprocable with reference to said plate; and pinions on said fans having a driving engagement with said annular member, whereby said frame is rotated upon operation of said fans.
